ACID STORAGE TANK AND THE LIKE

Phillip J. Weber, Jr., Montebello, Calif.

Application October 18, 1948, Serial No. 55,160

7 Claims. (Cl. 217—4)

2

This invention relates to tanks, and particularly pertains to an acid storage tank and the like.

Heretofore it has been common practice to store acid and other corrosive liquids in wooden containers or tanks. These tanks for the most part have been held together by the use of metal stay rods or bolts. In actual practice it has been found that the acid or other liquid migrates to the bolts and causes them to become weakened by corrosion. It is desirable to utilize a wooden tank due to its simplicity in construction and cheapness of material. It is the principal object of the present invention, therefore, to provide a wooden tank structure which may be assembled and held together by suitable fastening means, the structure being so designed as to insure that the metallic parts will be isolated from the corrosive liquid which is stored within the tank. It is also an object of the present invention to provide a wooden tank structure having details which will impart considerable strength to the walls.

The present invention contemplates the provision of a tank structure having a bottom and a plurality of elements joined together in a manner to form a wall, the device being further fitted with means for securing the upper and lower ends of said elements together and reinforcing them in a manner to form a strong wall assembly.

The invention is illustrated by way of example in the accompanying drawings in which:

Figure 1 is a view in perspective of an acid tank embodying the present invention.

Fig. 2 is a vertical sectional view of the end of the tank as seen on the line 2—2 of Fig. 1.

Fig. 3 is a vertical sectional view of the side of the tank as seen on the line 3—3 of Fig. 1.

Fig. 4 is a diagrammatic sectional view indicating the forces which act on the top and bottom rails on the side of the tank.

Fig. 5 is a diagrammatic view in plan indicating the top rail and showing the forces which act against this member under load or as a truss member to prevent the bulging of the sides of the tank.

Referring more particularly to the drawings, Fig. 1 shows the preferred form of the invention in a perspective view with sides 1, ends 2, and a bottom 3. The sides are composed of suitable planks 4 placed edge to edge and held together by a clamping means, such as a top rail 5 and a bottom rail 6, with tie rods 7 and compression posts 8. The ends are composed of suitable planks 9 placed edge to edge and held together

5 by a clamping means, such as a top rail 10, a bottom end skid 11, with tie rods 13, compression posts 15, and a bottom end sill 14. The bottom of the tank is composed of suitable planks 16 placed edge to edge and held in place by means of the bottom side rails 6 and bottom tie rods 17 which pass through the sides 1 at the bottom side rail 6 and underneath the tank, as shown in Fig. 3 at 18.

10 The edges of the planks 4, 9 and 16 are held in proper alignment by dowels 19 and sealed by splines 20 set in a suitable mastic 21.

The side top rail 5 is composed of a timber 22 laid flat and covered by a standard channel 23.

15 The compression posts 8 are secured thereto by means of either a mortice and tenon, chucked or doweled joint 24. The lower ends of the compression posts 8 are set on step 25 of a standard T section 26 which composes the bottom side rail 6 and is secured in place by means of the bottom tie rods 17. The end top rail 10 is similar to the side top rail 5 with compression posts 15 set between the lower edge of the top rail 10 and the upper edge of the bottom end skid 11

20 and are held in place by means of either a mortice and tenon, chucked or doweled joints 24 at both top and bottom. The bottom end skid 11 is notched at 27 on the interior face next to the end planks 9 to allow it to clear the tie rods 13

25 and fit snugly to the end 2. The compression posts 15 are bored at the proper locations 15a to allow end horizontal tie rods 28 to pass through and tie the sides 1 securely to the ends 2 at the corners 29 of the tank. Corner posts 30 act as compression posts for the side 1 as well as bolt bearing rails to receive end tie rods 28.

30 The bottom 3 of the tank is held securely in place by fitting into a side croze 31 in side 1 and resting on intermediate sills 32 and tie rods 17 and is prevented from buckling by the fact that ends 2 set in a croze 33 in the ends of bottom planks 16. The channels 23 of the top side rails 5 are coped at 34 to clear the channels of the end top rail 10 and to allow the ends 2 to be tightened independently of the sides 1. Intermediate bottom sills are secured to the tank by means of

35 a lip 35 which fits over the interior step of the T section 26. When the tank is properly tightened they are prevented from falling out and becoming lost in transit. However the length of the lip 35 is such as to form a space pocket 36 in order not to hinder the sides from seating properly onto the shaped edge of the bottom 3.

40 The bottom end skid 11 is secured to the tank by means of a lip 35 which fits over the interior step of the T section 26. When the tank is properly tightened they are prevented from falling out and becoming lost in transit. However the length of the lip 35 is such as to form a space pocket 36 in order not to hinder the sides from seating properly onto the shaped edge of the bottom 3. The top rail channels 23 are equipped with

45 50 55

lugs 37 to lag wooden cover pieces 38 in place in order to form a flat upper working surface 39 at the top edge of the tank. These cover pieces 38 can be easily removed to tighten the vertical tie rods.

Figure 4 shows a diagrammatic vertical section of the side wall forces acting on the top and bottom rails of the tank. P_5 indicates the force in tie rods 7 in tension. P_4 and P_3 indicate balancing compression forces as produced in the side planks and compression posts by the tension of tie rods 7. Pivot points —a— and —b— of the top and bottom rails are noted as being on the line of force of tie rods 7, indicating that the top and bottom rails act as rocker beams to equalize any difference in length of the compression posts and the built-up width of the side planks.

Figure 5 shows a diagrammatic view of the top rails when the tank is full, as noted by forces P_1 , denoting the tank contents and the balancing forces P_6 which counteract the tank load. In this case loads P_1 are counteracted by the resistance to bending action of the top rail 5 and transmitted equally to the set of horizontal tie rods at the ends of the tank or as tension value P_6 . In the case of the end top rail the forces P_1 are offset by the resistance to shear parallel to grain of the chimes of the side planks at the chime 12.

When the tank structure is assembled as disclosed in the drawings it is ready to be filled with acid or other liquid and will have the desirable functions previously described.

It will thus be seen that the tank here shown is simple in construction, may be easily assembled, and that the elements hold the parts of the tank in a manner to resist the weight exerted by the liquid contained in the tank and in a manner to prevent corrosion of the metallic parts used to fasten the tank.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. A tank structure comprising top rails extending the full length of the sides thereof, lower rail parallel to the top rails and coextensive therewith, intermediate wall sections, compression posts disposed between the top rail and the lower rail and interlocking therewith, and tie rods parallel to the compression posts secured through the top rail and the lower rail.

2. A tank structure comprising a bottom wall, a side wall formed of a plurality of planks placed edge to edge and joined together, top rails of channel shape extending the full length of the sides thereof, the legs of which extend downwardly, one leg extending along the inner face of the wall and the outer leg spaced therefrom, a lower rail of T-shape parallel to and coextensive with each top rail, the center web lying against the wall structure while the inner lower leg extends inwardly along the wall structure and the opposite lower leg extends outwardly from the web, a post, the upper end of which interlocks with the upper rail, and the lower end of which

rests against the web of the lower rail section, and a tie bolt extending downwardly along the outer face of the wall and being secured through the upper and lower rails intermediate the wall and the posts.

3. The structure of claim 2 including a second tie bolt extending beneath the floor and through the lower wall T section and post.

4. A tank structure of wooden type comprising a floor formed of a plurality of planks spaced edge to edge and side walls comprising a plurality of planks spaced edge to edge, the edges of said planks being splined together, a side croze formed in the lowermost plank of the side wall structure and receiving the ends of the floor planks, a metallic bottom rail extending the full length of each side wall formed by a T-shaped structural element fitting downwardly over the upper edge of the wall, posts disposed at spaced intervals throughout the length of the side walls, the upper ends of said posts interlocking with the channeled top rail and the lower ends of said posts resting against the outermost faces of the T-shaped lower rail, tie bolts passing through the lower ends of the posts and the lower rail to secure the posts in position, and vertical tie bolts extending downwardly through the channel-shaped upper rails to hold the posts in position and the rails of the side walls in their joined relationship.

5. A wall construction for wooden tanks comprising in combination; a plurality of interlocked longitudinally extending planks, a top rail engaging the topmost plank and coextensive with said plank, a bottom rail engaging the lowermost plank and coextensive with said plank, a compression post between said top rail and said bottom rail, and an intermediate tie rod extending between said top rail and said bottom rail and engaged therewith between the planks and the compression post.

6. A wall construction as set forth in claim 5 in which both of said rails include metallic beams having transversely extending portions engaging the top and bottom edges of the planks and extending outwardly therefrom to engage the compression post.

7. A wall construction as set forth in claim 5 in which the top rail includes a channel beam which receives the top edge of the planks and extends outwardly therefrom to receive the top end of the compression post and in which the bottom rail includes a T-shaped beam, one flange of which receives the lower edge of the planks while the other flange extends outwardly to receive the lower end of the compression post.
